UNITED STATES PATENT OFFICE.

CHARLES E. ROBERTS, OF OAK PARK, ILLINOIS.

DESIGN FOR A BARREL FOR BICYCLE-WHEEL HUBS.

SPECIFICATION forming part of Design No. 29,523, dated October 18, 1898.

Application filed September 7, 1897. Serial No. 650,852. Term of patent 7 years.

To all whom it may concern:

Be it known that I, CHARLES E. ROBERTS, a citizen of the United States, residing at Oak Park, in the county of Cook and State of Illinois,

have invented and produced a new and original Design for the Barrels of Bicycle-Wheel Hubs, of which the following is a specification, reference being had to the accompanying drawing, forming a part thereof.

As shown in the drawing, the leading or material feature of my design consists in a barrel for bicycle-wheel hubs provided with a bead, as shown at A, extending circumferentially around the center of the barrel, cir-

cumferential flanges extending around each end, as shown at B, and plain-surfaced portions between said center head and the end flanges.

Having described my invention, what I claim as new, and desire to secure by Letters Patent, is—

The design for the barrel of a bicycle-wheel hub, as shown and described.

CHARLES E. ROBERTS.
